UNITED STATES PATENT OFFICE.

WILLIAM DUNCAN AND MICHAEL JOHN DUFF, OF LOS ANGELES, CALIFORNIA.

SOFA PILLOW SIMULATING DOLL.

Application filed August 20, 1924. Serial No. 733,190.

This invention relates to improvements in sofa pillows.

It is a broad object of the invention to provide a pillow substantially in the form 5 of a doll or in the form of a bust of a person.

It is a further object of the invention to provide a sofa pillow constructed in the form of a doll or bust which has a ruffle 10 secured about the peripheral edge of the pillow which ruffle is adapted to extend around the head or face of the doll so as to simulate the appearance of a hood.

It is a further object of the invention to 15 provide a sofa pillow in the form of a doll having ruffles secured thereto, in which all of the ruffles are stitched in the seams of the faces forming the pillow so as to provide a neat and finished appearance.

With the foregoing and other objects in 20 view which will be made manifest in the following detailed description, reference is had to the accompanying drawings for an illustrative embodiment of the invention, 25 wherein

Fig. 1, is a front elevation of one form of the pillow.

Fig. 2, is a side or end elevation of the 30 pillow shown in Figure 1.

Figures 3, 4 and 5, are front elevations of 35 modifications of the pillow.

Figures 6 and 7 are partial sections showing the construction of the seam employed in constructing the improved pillow.

Referring to the accompanying drawings 40 wherein similar reference characters designate similar parts throughout, the pillows illustrated in Figures 1 to 5 inclusive in a most finished and complete form of construction are formed of two faces 10 and 11, the face 10 constituting the front face of the pillow and the face 11 constituting the back face of the pillow. Each face 10 and 11 is formed of two pieces, the face 10 being 45 formed of a body portion 12 and a head portion 13, and the face 11 is formed of a body portion 14 and a head portion 15.

Upon the head portion 13 which constitutes one of the parts forming the front 50 face 10 of the pillow, there may be stenciled, printed or painted a face substantially as shown. This face may be a girl's face or a boy's face, or may even be in the form of the face of an animal. However, in the preferred form of construction, the face con-

stitutes a girl's face substantially as shown.

The body portion 12 and the head portion 13 are secured together with their front or exposed surfaces facing each other as illustrated in Figure 6.

A ruffle 16 is secured or stitched between the body portion 12 and the head 13 so that as illustrated in Figure 7, when the head portion 13 is folded back from the body portion 12, the ruffle 16 will have its base 60 65 portion 16^a secured between the inturned edges 17 and 18, forming an inturned seam between the body portion 12 and the head portion 13, forming a neat exterior appearance. The body portion 14 and the head portion 15 of the back face 11 are 70 stitched together with a ruffle 19 secured between the inturned seam in substantially the same manner.

In the actual construction, as the front 75 face and the back face is formed, these faces are placed one upon the other so that their exposed or exterior surfaces are facing each other and the edges of the front and back faces are stitched together in similar manner to that in which the body portion 12 and the head 13 are secured together so that a ruffle 20 is secured around the peripheral edge of the pillow with its base portion 80 extending between the inturned edges of the front and back faces, which forms an inturned seam.

In securing the front and back faces together, a small opening is left preferably in the bottom of the pillow as indicated between O and O' of Figure 1. As the front and back faces are stitched together inside out, the pillow may then be turned outside in through the opening left between O and O'. This opening O—O' also serves as a 90 means for admitting stuffing S to the interior of the pillow, after which this opening may be closed by hand stitching.

It is seen that by constructing a pillow in this manner that a sofa pillow is provided 100 which has a ruffle extending around the periphery thereof and across the faces thereof, so that an inturned seam is provided at every point of attachment of the ruffle and that the base of the ruffle is secured between the edges forming the inturned seam.

The body of the pillow may take various forms, some of which are illustrated. The form in Figure 1 is provided with a pair of 105 opposed legs 21 and 22, whereas the modi- 110

fications shown in Figures 3, 4 and 5, the body is shown as being substantially triangular, square and circular respectively.

It is to be understood that various changes can be made in the actual construction of the improved pillow depending upon whether the smooth or finished exterior surface is desired. In some cases, the front face 10 and back face 11 may have their body and head portions integral with each other with the ruffle 16 hand stitched to the face of these faces. Also the ruffle 20 could have its base portion merely stitched to the exterior of the seam between the front and back faces. However, to provide a finished pillow, it should be constructed with inturned seams with the ruffles having their base portions secured between the edges forming the in-turned seams, as has been previously described.

The opposite legs 21 and 22 of the pillow shown in Figure 1 co-operate to form a recess 23 in the bottom side of the pillow which recess is adapted to conform with a person's shoulders when lying upon his side with his head resting upon the pillow.

It is to be understood that various changes in the details of construction may be made without departing from the spirit or scope of the invention as defined by the appended claims.

What we claim is:

1. A sofa pillow comprising a front face and a back face, each of said faces being

formed of two pieces, one of which constitutes a body portion and the other of which constitutes a head portion, the pieces of each face having their contiguous edges stitched together to provide an inturned seam, a ruffle having its base secured between the edges forming said inturned seam, said front and back faces having their edges stitched together to provide a second inturned seam and a second ruffle extending peripherally around said pillow, said second ruffle having its base portion secured between the edges of the faces forming said second inturned seam.

2. A sofa pillow comprising a front face and a back face, one of said faces being formed of two pieces, one of which constitutes a body portion and the other of which constitutes a head portion, the pieces of the mentioned face having their contiguous edges stitched together to provide an in-turned seam, a ruffle having its base secured between the edges forming said inturned seam, said front and back faces having their edges stitched together to provide a second inturned seam, and a second ruffle extending peripherally around said pillow, said second ruffle having its base portion secured between the edges of the faces forming said second inturned seam.

In testimony whereof we have signed our names to this specification.

WILLIAM DUNCAN.
MICHAEL JOHN DUFF.
